UNITED STATES PATENT OFFICE.

P. FLETCHER COLE, OF NEWARK, NEW JERSEY.

GLOVE, &c.

SPECIFICATION forming part of Letters Patent No. 334,513, dated January 19, 1886.

Application filed August 3, 1885. Serial No. 173,343. (No model.)

To all whom it may concern:

Be it known that I, P. FLETCHER COLE, a citizen of the United States, residing at Newark, in the county of Essex and State of New Jersey, have invented certain new and useful Improvements in Gloves, Mittens, &c.; and I do hereby declare the following to be a full, clear, and exact description of the invention, such as will enable others skilled in the art to 10 which it appertains to make and use the same, reference being had to the accompanying drawings, and to letters of reference marked thereon, which form a part of this specification.

15 The object of this invention is to provide a convenient and secure pocket or receptacle in a glove, mitten, or mit, in which change or other small articles can be placed for ready access; and it consists in a glove, mitten, or 20 mit having a pocket therein, substantially as illustrated in the drawings, described in the specification, and finally embodied in the clause of claim.

In the drawings, Figure 1 is a view of a hand, &c., having a glove thereon which is 25 provided with a pocket; and Fig. 2 is a sectional view on the line *x* of Fig. 1, through the pocket.

Similar reference-letters indicate corresponding parts in both of the figures.

The glove shown in the drawings to illustrate my invention is a right-hand glove; but the pocket may be made in either the right-hand or left-hand glove, or both. The pocket 35 *a* is formed in the palm of the hand, so that the fingers can close down upon the mouth thereof. The said pocket is preferably formed by cutting a slit or opening in the palm of the glove and sewing a re-enforcing piece, *b*, 40 around the edge thereof, to prevent the tearing of the material of the glove. On the under side of the palm of the glove is sewed a piece of material, *c*, similar to that from which the glove is made, or of any suitable description, as dotted on Fig. 1 or shown in section in Fig. 2, forming the receptacle or pocket. The said piece *c* may be so sewed to the glove that the mouth shall be in the center thereof, but is preferably so attached that the 45 pocket extends in its longest direction toward the fingers, as indicated by the dotted lines of Fig. 1. This is preferred, as it secures the

greatest safety to the contents of the pocket, since the natural position of the hands in walking is hanging down at the sides of the 55 body, so that the mouth becomes the top of the pocket, similar to an ordinary pocket in a coat or other garment. The advantage of placing the pocket in the palm of the glove is, that by contracting the hand the glove is relaxed, so that the mouth may be easily opened and any small article inserted in the pocket, but on permitting the hand to return to its normal position the glove tightens across the palm, closes the mouth, and thereby effect- 60 ally prevents the contents of the pocket from escaping therefrom. Furthermore, security is made still more certain by placing the pocket in the palm of the glove, as the fingers may be closed down upon the mouth, as will be 65 readily perceived by referring to Fig. 1.

I am aware that it is not entirely new to place a pocket in a glove; but it has been formed on the gauntlet of the glove, and not as I purpose placing it, not having the advantages possessed by my arrangement, as hereinbefore specified. The pocket in the gauntlet requires a flap or some other means to close the mouth, while my arrangement utilizes the natural movement of the hand. 80

I am also aware that gloves, mits, &c., have been made with pockets therein for holding small articles—such as coins, &c.—to which access is had through the palm and at the wrist; but in the glove referred to, having an 85 opening in the palm, the said mouth or opening is in the center of the pocket, while in my improved glove the mouth is at one end of the pocket, which extends toward the fingers, and articles placed therein are more effectually 90 prevented from escaping, since the natural position in walking is with the hands hanging downward, and when the fingers are closed they hold the coins under the same. In the glove having a pocket extending toward the fingers, the mouth thereof is at the 95 wrist, so that to enable the fingers to close upon and hold the coins the pocket must necessarily be made very deep, which prevents the coins from being easily removed from the 100 pocket and renders the device impracticable. Moreover, the coat-sleeve interferes in getting into the pocket when the mouth is at the wrist. Another advantage which my improved

glove possesses, and which results from extending the pocket toward the fingers, is, that by bending the fingers over toward the wrist the flesh at the base of the fingers rises and 5 pushes the coins in the pocket toward or partly protruding from the mouth thereof, and permitting the easy withdrawal of the coin. This cannot be done when the mouth is in the center of the pocket or at the wrist, 10 as the coins are not directed by the shape of the pocket toward the fingers, which is necessary to produce the desired result. As the pocket is intended especially for kid gloves, this pushing outward of the coin is very desirable, as it is otherwise very difficult to get at the coin, because of the tightness of the 15 glove.

Having thus described my invention, I desire to claim the following:

20 As an improved article of manufacture, a

glove or mit having an opening in the palm thereof which constitutes the mouth of a pocket, said opening extending the entire width of the same and being provided with a re-enforcing piece around the edge thereof, 25 and having a piece of suitable material secured to the back of the palm within the glove around the opening in the palm, forming a pocket or receptacle which extends in the direction of its greatest length toward the fingers, substantially as and for the purposes set forth.

In testimony that I claim the foregoing I have hereunto set my hand this 1st day of August, 1885.

P. FLETCHER COLE.
